UNITED STATES PATENT OFFICE.

FENTON B. FLEMING, OF LINCOLN, NEBRASKA.

BEAD-FASTENER.

1,177,505.

Specification of Letters Patent. Patented Mar. 28, 1916.

Application filed February 10, 1916. Serial No. 77,451.

To all whom it may concern:

Be it known that I, FENTON B. FLEMING, citizen of the United States, residing at Lincoln, in the county of Lancaster and State 5 of Nebraska, have invented certain new and useful Improvements in Bead-Fasteners, of which the following is a specification.

This invention has relation to beads as used in jewelry, and has for its object to 10 provide a more practical and efficient means for fastening and unfastening a string of beads in the every-day use of the wearer; to provide a more efficient and practical means for holding the ends of the cord or 15 chain on which the beads are strung; and to combine the above advantages in a design having all of the parts interchangeable, entirely contained within the beads, and renewable without the use of heat, weld, 20 solder, cement, wax or braze.

The parts are so arranged that the mechanisms are concealed and the clasp device may be operated without the use of levers or 25 pressure catches, it being merely necessary to press the parts firmly together to accomplish the fastening and to pull the parts persistently apart to accomplish the unfastening.

For a full understanding of the invention 30 reference is to be had to the following description and accompanying drawing, in which:

Figure 1 is a side elevation of the fastening as applied; Fig. 2 is a sectional view of 35 the fastening.

Further objects and advantages will appear in the following description, it being understood that various changes may be made in the construction, arrangement and 40 combination of the parts without departing from the scope of the appended claims.

Corresponding and like parts are referred to in the following description and indicated in all the views of the accompanying 45 drawing by the same reference characters.

In operation, the beads constituting the necklace, bracket or what-not are strung on a suitable cord or chain 1 in the ordinary manner and each of the two ends of 50 the string or chain is then passed into one of the parts forming one half of my fastening device where it is held firmly in place by the rounded end of a screw as illustrated clearly in the drawing at Fig. 2.

55 In holding the ends of the string as heretofore practised, the string is either ce-

mented, soldered or waxed under the action of heat which burns the gold or singes the string. Also the solder or cementing material often runs down into the catch device mechanism and clogs it so that it will not operate properly. These disadvantages are obviously impossible with my improved design, and my device has a more positive grip on the cord or chain, it requiring a 60 pull sufficient to break the texture of the cord or chain before giving away.

65 My complete fastener consists of two main portions, each comprising one entire bead integral with a half bead so that when 70 brought together they form three complete beads which are rigid and possess no flexure between. This design enables the wearer to locate the fastening very readily when worn about the neck or other part of the 75 person where it is unhandy or impossible to scan the joints with the eye when unfastening the clasp; for, the beads being exactly similar to the other beads comprising the string it would be exceedingly difficult to locate the joint through the sense of touch unless aided by the stiffness of the 80 three beads.

The beads comprising the fastening are 85 preferably made to correspond to the beads now in use in the ordinary trades, so that when used with such bead strings the whole string shall conform exactly in size, polish and configuration.

A fastening method for clasping and unclasping the string of beads is a necessary 90 part of the complete device and this part of the invention is accomplished as follows: Referring particularly to Fig. 2, the flange 7 being screwed into the bead 4 provides a 95 collar or shoulder 8 for holding the other bead in true alinement when the two parts are brought together. The flanges 7 and the screws 3 and 5 are never unscrewed in the every-day operation of the wearer. The 100 flange 7 is provided centrally with tube like projections 9 and 10 which act as a guide and receptacle for the male projection 6 integral with the bead 2, the tube part 9 being shaped to facilitate the entrance of the 105 male member 6 and the tube part 10 being slotted on opposite sides of its outer periphery for the reception of a steel wire spring 6' shown clearly in Fig. 2. The 110 male member 6 is provided on its outer periphery with a beveled annular groove 6^a which engages the aforementioned spring

with a more or less positive grip when inserted in the female part 10 in the operation of clasping the string of jewelry.

Since the beveled groove extends entirely around the male projection 6 it will be seen that the beads may be severally rotated when in a clasped condition, the spring thus encountering an infinite number of wearing surfaces to the end that a much longer life 10 of the device is attained.

In case the spring becomes worn or broken it may be reached for renewal or repairs by unscrewing the flange 7 from the bead 4, otherwise the flange 7 is considered by the wearer as integral with the part 4, and serves as a protection and concealment for the spring to prevent foolish or meddlesome tampering with the same.

This application is a substitute for applicant's earlier application Serial Number

651,402, filed September 26, 1911, and renewal application Serial Number 857,950, filed August 21, 1914.

Having thus described the invention, what is claimed as new is:

A jewelry fastening comprising a string, a hollow member having an aperture receiving said string, and a screw aligned with said aperture and adjustably engaging the hollow member at a point diametrically opposite the aperture and adapted to bear against the string to clamp the same against the inner side of the member.

In testimony whereof I affix my signature in presence of two witnesses.

FENTON B. FLEMING.
